UNITED STATES PATENT OFFICE.

WILLIAM BATES PINKERTON, OF COTTONPLANT, ARKANSAS.

PROPELLER.

SPECIFICATION forming part of Letters Patent No. 678,275, dated July 9, 1901.

Application filed December 31, 1900. Serial No. 41,682. (No model.)

To all whom it may concern:

Be it known that I, WILLIAM BATES PINKERTON, a citizen of the United States, residing at Cottonplant, in the county of Woodruff and State of Arkansas, have invented 5 certain new and useful Improvements in Propellers; and I do hereby declare the following to be a full, clear, and exact description of the invention, such as will enable others skilled in the art to which it appertains to 10 make and use the same.

My invention relates to certain new and useful improvements involved in the construction of propellers; and my object is to 15 provide reliably efficient mechanism of the character specified which will enable great power to be applied to the propulsion of a vessel through the water, and while I shall confine my description in the following specification to a simple application of my invention 20 to the stern of a vessel it will be understood that it may be variously applied to use.

In the accompanying drawings, Figure 1 is a side view of my invention complete, showing 25 the same as applied to use upon the stern of a vessel, while Fig. 2 is a rear elevation thereof, showing the propellers occupying various positions.

In order to conveniently designate the several features of my invention and their co-operating accessories, numerals will be employed, of which 1 indicates the stern of a vessel of the usual or any preferred construction, while 2 designates a suitable beam or 35 portion of the framework, which preferably extends rearwardly sufficiently to form a bearing-seat for the driving-shaft 3.

It will be understood that the beams 2 are placed upon each side of the vessel and may 40 be disposed at intervals between, if deemed desirable, the object being to provide a thoroughly reliable support for the crank-shaft 3, which is so shaped that preferably a plurality of crank-sections 4 will be provided.

45 In Fig. 2 I have illustrated the middle portion of the shaft as being further sustained and supported by a cross-beam 5, extending under the beams 2 and properly sustained in its operative position in any desired way.

50 Designed to coöperate with the plurality of crank-sections 4 are the propeller-arms 6,

which may be multiplied in number as deemed most desirable, it being understood that the disposition of the several crank-sections 4 is such that the lower ends of the arms 6 will 55 be alternately or successively disposed within and drawn upward out of the water, the latter being designated by the numeral 7 in Fig. 1.

Upon the lower end of each of the arms 6 60 I secure in any preferred way, as by the bolts 8, the cup-shaped propelling vessels or blades 9, which are preferably so formed as to have a continuous radially-disposed flange or rim-section 10, the object of said rim being to enable 65 the blade to engage the water and enable the arms to more efficiently perform their office of propelling the vessel or contributing to the propulsion thereof. The upper end of each of the arms 6 is held in its operative position by means of the lever-sections 11, said arm and lever being pivotally united, while the opposite end of the lever-sections 11 are pivotally secured in place by a rod 12, which latter is secured in position upon the framework 70 comprising the vertical section 13 and the brace-sections 14, as clearly shown in Fig. 1. The lower end of each of the arms 6 is disposed normally outward or rearward by means of the spring-section 15, which is properly 75 secured in position, as by the bolts 16 and 17. In order to more securely hold the upright 13 in place, I provide the rod 18, thus constituting a secure piece of bridgework which will securely strengthen and sustain 80 the several coöoperating parts of my propelling apparatus.

Each of the springs 15 is so bent and shaped that the lower end of the arm 6, to which it is attached, will be normally disposed rearwardly to the full extent of its possible movement, and it therefore follows that while the blade is passing through the water the force of the spring will be applied to the arm in such a way that said blade will be forced 90 rearwardly. It is further obvious that when the blade has been raised out of the water by the action of the crank-shaft to which the arm carrying the blade is secured, as the arm is drawn inward by the crank-shaft the spring 95 will be again bent upon itself, so that when the blade again goes downward into the water 100

the force of the compressed spring will be utilized to again drive the blade rearwardly.

While I have described my improved propeller in coöperation with the auxiliary spring 5 15, I desire to use the propeller with or without said spring, as I may find most desirable in practice. By bolting the spring-sections 15 in place they may be readily removed and renewed as desired. By pivotally connecting the upper ends of the arms 6 to the levers 11 by means of the bearing-plates 19, one of said plates being upon either side, a very simple form of bearing is provided, inasmuch as a simple bolt 20 may be passed through 15 suitable apertures in the ends of the bearing-plates and through the upper end of the arm 6, it being understood that sufficient play will be left between the bearing-plates to afford a perfect bearing-seat.

20 By multiplying the crank-sections 4 as desired upon the shaft 3 any preferred number of arms 6 may be mounted in position. It will be understood that the shaft 3 may be driven in any preferred way, as by a suitable 25 piston 21, or said shaft may be operatively connected to the driving-power by other preferred means.

While I have described the preferred construction and combination of parts deemed 30 necessary to materialize my invention, it will

be understood that I desire to comprehend all such substantial equivalents and substitutes as may fall fairly within the scope of my invention.

Having thus fully described my invention, 35 what I claim as new, and desire to secure by Letters Patent, is—

The herein-described propeller comprising a driving-shaft having a plurality of crank-sections; a plurality of arms coöperating with 40 said crank-sections adapted to be operated by the rotation of said shaft; a series of levers pivotally connected to the upper ends of said arms, a cup-shaped blade attached to the opposite end of each of said arms, and a 45 spring so mounted in position at the point of pivotal union of said lever and arm whereby the lower end of the arm will be normally extended rearwardly; the spring being designed to facilitate the movement of the blade carried by the arm through the water, all combined substantially as specified and for the purpose set forth.

In testimony whereof I affix my signature in presence of two witnesses.

WILLIAM BATES PINKERTON.
